Wes. 588

Julius Holzer of Philadelphia Pa
Assignor to
North. Chase & North of Philadelphia Pa
Letters Patent No 588. Dated August 2^d 1853,

The Schedule referred to in these Letters Patent and making
part of the same.

To all whom it may concern:

Be it known that I, Julius Holzer, of the City and County of Philadelphia and State of Pennsylvania, have invented a new and original design for a cooking Stove, and I do hereby declare that the following is a full and exact description thereof, reference being had to the accompanying drawings making part of this Specification; in which Fig 1. represents a side plate of said Stove, Fig 2. a front plate, Fig 3. a foot, and Fig 4 a portion of the bottom plate of the same. Little letters refer to like parts in each figure.

b, b, b, are oblong raised panels and d, d, f, f, are curved raised panels. Each panel is bordered by mouldings, and is ornamented by a combination of pyramids, a, c, and prisms, e. The base of the smaller pyramids, c, corresponds - in its line or dimensions with the -

width of the prisms e. which are adjacent to them. Each side of the base of the larger pyramids. a. is of like line or dimensions with the length of the adjacent prisms. The lower portion and one side of the side plate, and the foot, are also ornamented with a similar combination of pyramids and prisms. The bottom plate is surrounded with a shell and dragon-tongue moulding. f.

What I claim as my invention and desire to secure by Letters Patent, is the design and configuration of the ornaments and mouldings herein described, forming an ornamental design for a Cooking Stove.
